TIRE

Harold D. Fetty, Birmingham, Mich., assignor to The
Goodyear Tire & Rubber Company, Akron, Ohio

Filed Dec. 3, 1971, Ser. No. 204,792

Term of patent 14 years

Int. Cl. D12—15

U.S. Cl. D12—151

The figure is a perspective view of a tire showing my new design, it being understood that the design is repeated throughout the circumference of the tire, the opposite side being substantially the same as that shown.

I claim:

The ornamental design for a tire, substantially as shown and described.
